Photographs F and G of a convex mirror marked with Patent No. D 305,808.

Primary Examiner—Ralf Seifert

Attorney, Agent, or Firm—Fitch, Even, Tabin & Flannery

[57] CLAIM

The ornamental design for an adjustable convex mirror, as shown and described.

DESCRIPTION

FIG. 1 is a side perspective view of an adjustable convex mirror showing my new design;
 FIG. 2 is a front elevational view thereof;
 FIG. 3 is a top plan view thereof;
 FIG. 4 is a bottom plan view thereof;
 FIG. 5 is a rear elevational view thereof;
 FIG. 6 is a side elevational view;
 FIG. 7 is a second side elevational view opposite the side shown in FIG. 6; and,
 FIG. 8 is a front elevational view with the front reflective mirror panel removed.
